UNITED STATES PATENT OFFICE.

ALBERT NICHOLAS LANDGRAF, OF WASECA, MINNESOTA, ASSIGNEE OF ONE-THIRD TO
SYLVESTER J. MATZ, OF WASECA, MINNESOTA.

FLOOR-LAYING TOOL.

1,159,963.

Specification of Letters Patent.

Patented Nov. 9, 1915.

Application filed April 17, 1914. Serial No. 832,602.

To all whom it may concern:

Be it known that I, ALBERT NICHOLAS LANDGRAF, a citizen of the United States, residing at Waseca, in the county of Waseca and State of Minnesota, have invented certain new and useful Improvements in Floor-Laying Tools, of which the following is a specification.

This invention relates to new and useful improvements in floor laying tools, and has for its principal object to provide a tool which will engage the floor boards and force the same into position without in any way injuring the boards.

Another object of the invention is to eliminate the danger of injuring the tongues on floor boards.

A still further object of the invention is to provide a flooring tool which will also serve as a nail punch to insure the nails being properly placed and firmly driven in position.

With these and other objects in view the invention consists in the novel combination and arrangement of parts which will be fully set forth in the following specification and accompanying drawing, in which:

Figure 1 is a side view in elevation of a tool constructed in accordance with this invention, showing the same as it would appear when in use in laying flooring, and Fig. 2 is a top plan view of Fig. 1.

Referring now to the drawings by characters of reference the numeral 1 designates a piece of flooring of the usual construction which is provided with the ordinary tongue 2 and groove 3, the floor laying tool, which is designated usually by the numeral 4, is shown in position on the floor board 1 and 40 will be more fully hereinafter described.

The floor laying tool 4 preferably comprises the main body portion 5 having formed at one of its side edges the forward extension or toe portion 6, which is preferably segmental in cross section and terminates in curved end 7, which is clearly

illustrated in Fig. 1. The edge of the body portion 5 opposite the toe portion 6 is provided with the heel portion 8 forming the shoulder 9 which engages the edge of the 50 floor board when the same is being put in place and serves as a nail punch to drive the nail heads home. A suitable cut out portion is formed near the inner edge of the heel portion 8 and is so arranged that it 55 forms the shoulder 10, which is spaced from the shoulder 9 a distance sufficient to accommodate the tongue 2 of the floor board. Extending upwardly and angularly from the body portion 5 is the anvil 11 which terminates in the enlarged striking head 12 to provide a striking surface against which the user hammers.

It will be apparent from the foregoing that in use the device is set on the floor 65 board as illustrated in Fig. 1 and upon repeated blows on the head 12 the board will be firmly driven in place so that the tongue of the adjacent board will enter the groove in the board which is being positioned. Owing to the fact that the shoulder 9 lies against the floor board 1 at the point where the tongue 2 engages the same it will be apparent that the nail, which is indicated in the dotted lines in Fig. 1, will be 75 driven home and the use of the ordinary type of nail punch eliminated. Should the user be forced to discontinue use of the tool in the manner above referred to because of the fact that the wall of the building in 80 which the flooring is being laid interferes with the operation the toe portion 6 may be brought into operation and used to pry the boards together.

While in the foregoing there has been 85 shown and described the preferred embodiment of this invention it is to be understood that such changes in the combination and arrangement of parts as may fall within the scope of the claim may be resorted 90 to without departing from the spirit and scope of the invention.

Having thus described the invention what is claimed as new, is:

A floor laying tool comprising an elongated body, a toe portion formed on and extending forwardly from one side edge of the body, a heel portion formed at the other side edge of the body and extending to a point near the side edge on which the toe portion is formed, the lower forward edge 10 of the heel portion being cut away, an anvil

extending upwardly and rearwardly from the body and a striking head at the upper end of the anvil.

In testimony whereof I affix my signature in presence of two witnesses.

ALBERT NICHOLAS LANDGRAF.
